UNITED STATES PATENT OFFICE.

WILLIAM B. CAROLUS, OF STERLING, ILLINOIS.

BOLT AND NUT CUTTER.

SPECIFICATION forming part of Letters Patent No. 710,181, dated September 30, 1902.

Application filed May 19, 1902. Serial No. 108,044. (No model.)

To all whom it may concern:

Be it known that I, WILLIAM B. CAROLUS, a citizen of the United States, residing at Sterling, in the county of Whiteside and State of Illinois, have invented a new and useful Improvement in Bolt and Nut Cutters, of which the following is a specification.

My invention relates particularly to combination bolt and nut cutters; and my primary object is to provide a thoroughly practical construction for such implements, particular attention being paid to securing cheapness, simplicity, great strength, and efficiency.

The invention is illustrated in its preferred embodiment in the accompanying drawings, in which—

Figure 1 is a perspective view of a complete bolt and nut cutter; Fig. 2, an enlarged broken section parallel with a side of the cutting-head, the section being taken as indicated at line 2 of Fig. 6; Fig. 3, an end view of the cutting-head; Figs. 4, 5, and 6, sections taken as indicated at the corresponding lines of Fig. 2, and Fig. 7 a view of a block employed in the adjustment of the reciprocable bolt-cutting knife.

The preferred construction is as follows: A represents a blade or cutter frame comprising members A' A², formed from sheet metal; B, a block secured in the frame A at the free end thereof and supplied with a bolt-cutting blade having a sharp edge a parallel with a side of the frame and provided also with a dull nut-bearing edge a', perpendicular thereto; C, a reciprocable blade-attaching block movable longitudinally of the frame; C', a bolt-cutting blade having a sharp cutting edge b directly opposed to the blade a; C², a bolt cutting or splitting blade having a sharp cutting edge b' directly opposed to the nut-bearing edge a'; D, short links pivotally connected with the frame member A', and D' levers having enlarged ends slotted to receive the rear ends of the links D and lugs or ears c, with which the block C is provided at its rear end or base. The links are connected by pivots d with the frame member A' and by pivots d' with the levers D', and the levers are connected by pivots d² with the base of the block C.

The frame member A' is integrally formed from sheet metal and is of general U shape,

affording sides f and a connecting-web f', the latter constituting the end of the implement. The sides f are spaced to receive the block C between them and are provided with longitudinal slots or openings f², one of which has an enlargement f³ at its rear portion. The rear extremities of the sides f are provided with laterally-projecting ears f⁴, corresponding sets of which receive between them the enlarged front ends of the links D. In the operation of stamping out or blanking the frame member A' the lateral edges are provided with recesses which produce, after forming, the cut-away or sheared corners f⁵.

The frame member A² comprises a U-shaped strip with parallel lateral edges and integrally-stamped lateral lugs g, which pass through corresponding perforations, with which the member A' is provided, and serve as rivets. Thus the member A² is in reality a U-shaped spacing-piece, having sides g' and a web g², the latter lying adjacent to the inner surface of the web f'. The web g² reinforces the end of the frame, and the complete member A² firmly connects the sides of the member A' and affords with the member A' a box-frame open at the top and bottom (at the slots f²) and open at the rear end to receive the block C. As shown in Fig. 4, the sides g' form guides for the lateral edges of the block C and are so located with relation to the longitudinal walls of the slots f² that flanges h are left to form top and bottom guides for said block C. The block C has its upper and lower front portions cut away, leaving a projection k of reduced cross-section, at the base of which are transverse shoulders k' k². The blade C² is formed with a shoulder k³, which abuts against the end of the projection k, and it has a rearward extension k⁴, which abuts against the shoulder k'. The extensions k k⁴ are provided with registering vertical slots k⁵. The blade C' abuts at its base end against the shoulder k² and has a threaded perforation receiving a screw k⁶, extending through the slots k⁵. When the screw is tightened, a connection is formed capable of transmitting great compressive force from the levers. The bolt-knives are subjected to great wear and must be frequently ground, while there is little wear upon the nut-blades. The construction permits the

bolt-knife C' to be adjusted as required, a wedge or block l of desired thickness being inserted between the rear end of the blade and the shoulder k². To hold the block in place, the shoulder k² is undercut and the block is provided with a lip, as shown in Fig. 7.

The blade B fits between the sides g' of the member A² and has top and bottom projections which fit in the slots f² of the top and bottom plates f. Said blade is inserted at the enlarged opening f³ and moved forward into position, being secured by a screw m. The blade C' has its lateral edges in contact with the sides g' and has a projection n, fitting snugly between the flanges h. Said blade is inserted from the rear and then raised into position. The blade C² has its lateral edges in contact with the sides g' and has a projection n', which fits snugly between the flanges h. Said blade is inserted from the rear and then raised into position, the block C being inserted lastly and the screw inserted to secure the blades thereto.

25 The manner of using the implement will be readily understood from the foregoing detailed description. When a bolt is to be clipped, the implement is placed so that the bolt projects between the cutting edges a and b. When a nut is to be split, the implement is reversed, so that the vertical edges a' b' engage the nut. In the operation of "splitting" the nut the blunt edge a' acts as a bearing, while the sharp edge b' cuts into the nut approximately to the bolt and causes the walls of the cut to separate, the two halves of the nut swinging about the bearing a'.

An implement constructed as described is capable of withstanding great strain, is cheap, 40 and thoroughly efficient.

Changes in minor details of construction within the spirit of my invention may be made. Hence no undue limitation should be understood from the foregoing detailed description. For instance, a less desirable but still valuable construction within the spirit of my invention would result if either of the frame members A' and A² were altered so as to be no longer integral, and even if both 45 were thus altered valuable features of the invention would remain.

What I regard as new, and desire to secure by Letters Patent, is—

1. In an implement of the character described, a cutter-frame comprising suitably-spaced sheet-metal side plates connected at one end, and sheet-metal connection joining said side plates rigidly together and forming therewith a box open at one end, for the purpose set forth.

2. In an implement of the character described, a cutter-frame comprising suitably-spaced sheet-metal side plates connected at one end, and sheet-metal connection joining 65 said side plates rigidly together and forming therewith a box open at one end, said first-named plates having pivot-perforations at

their rear extremities, for the purpose set forth.

3. In an implement of the character described, 70 a frame comprising a U-shaped sheet-metal member with integrally-formed sides and end web, and separately-formed connecting means joining said sides firmly together, for the purpose set forth.

4. In an implement of the character described, 75 a frame comprising top and bottom side plates and a U-shaped sheet-metal strip secured between said plates, for the purpose set forth.

5. In an implement of the character described, 80 a frame comprising top and bottom side plates, and suitably-spaced sheet-metal members having lugs formed integrally therewith and passing through perforations in said side plates and riveted in place, for the purpose set forth.

6. In an implement of the character described, 85 a frame comprising a U-shaped sheet-metal member with integrally-formed side plates and end web, and suitably-spaced sheet-metal plates having lugs at their lateral edges secured in perforations in said first-named member, for the purpose set forth.

7. In an implement of the character described, 90 a frame comprising a U-shaped sheet-metal member with integrally-formed side plates and end web, and a U-shaped connecting member with integrally-formed sides and connecting end web, said last-named member forming a box with said first-named member, for the purpose set forth.

8. The combination with a stationary blade, a reciprocable blade, and a pair of levers, of a frame, comprising a U-shaped sheet-metal member having integrally-formed side plates and connecting end web, said last-named member having lever-connecting means at the rear extremities of its side plates, and connecting means joining said side plates rigidly together, 105 for the purpose set forth.

9. In an implement of the character described, 110 a frame comprising a U-shaped sheet-metal member with integrally-formed side plates and end web, a U-shaped connecting member with integrally-formed sides and connecting end web, said last-named member forming a box with said first-named member, and having lugs on its lateral edges connected 115 with the side plates of said first-named member, for the purpose set forth.

10. In an implement of the character described, 120 the combination with a frame, a fixed blade, and a pair of levers, of a reciprocable block connected with said levers and having a forward extension of reduced cross-section with shoulders at its base, and blades secured to said block and having abutting shoulders, for the purpose set forth.

11. In an implement of the character described, 125 the combination with a frame, a fixed blade, and a pair of levers, of a reciprocable block connected with said levers and having a forward extension of reduced cross-section

with shoulders at its base, a nut-cutting blade with an extension abutting against a shoulder at the base of said first-named extension and a shoulder abutting against the end of said first-named extension, a second blade abutting at its base against the remaining shoulder at the base of said first-named extension, and a connecting-screw, for the purpose set forth.

12. In an implement of the character described, the combination with a frame, a fixed blade, and a pair of levers, of a reciprocable block connected with said levers and having a forward extension of reduced cross-section

with shoulders at its base, a nut-cutting blade with an extension abutting against a shoulder at the base of said first-named extension and a shoulder abutting against the end of said first-named extension, a second blade abutting at its base against the remaining shoulder at the base of said first-named extension and a connecting-screw, said last-named blade being adjustable, for the purpose set forth. 15

WILLIAM B. CAROLUS.

In presence of—

ALBERT D. BACCI,
M. S. MACKENZIE.
